CLAIM

The ornamental design for a gasket scraper, as shown and described.

DESCRIPTION

FIG. 1 is a top plan view of an ornamental design for a gasket scraper of the present invention;

FIG. 2 is a front view of an ornamental design for a gasket scraper of the present invention;

FIG. 3 is a right side view of an ornamental design for a gasket scraper of the present invention;

FIG. 4 is a rear view of an ornamental design for a gasket scraper of the present invention;

FIG. 5 is a left side view of an ornamental design for a gasket scraper of the present invention;

FIG. 6 is a bottom plan view of an ornamental design for a gasket scraper of the present invention;

FIG. 7 is an upper front end isometric view of an ornamental design for a gasket scraper of the present invention;

FIG. 8 is a lower front end isometric view of an ornamental design for a gasket scraper of the present invention;

FIG. 9 is a rear end isometric view of an ornamental design for a gasket scraper of the present invention;

FIG. 10 is a bottom view of an ornamental design for a gasket scraper of the present invention;

FIG. 11 is a cross-section view taken from line 11-11 of FIG. 10 of an ornamental design for a gasket scraper of the present invention; and,

FIG. 12 is a cross-section view taken from line 12-12 of FIG. 10 of an ornamental design for a gasket scraper of the present invention; and

1 Claim, 10 Drawing Sheets
